SPRING-ACTUATED CLOTHESPIN

Alf Otto Hellqvist, Stockholm, Sweden, assignor
of thirty per cent to Nils Ericsson, Vagnharad,
Sweden, and thirty per cent to Axel William
Hauffenan, Stockholm, Sweden

Application February 29, 1948, Serial No. 12,182
In Sweden December 9, 1946

Section 1, Public Law 690, August 8, 1946
Patent expires December 9, 1966

3 Claims. (Cl. 24—137)

1

This invention relates to spring actuated clothes pins or the like comprising two jaws held together by a member encircling the same, said member being actuated by a resilient member keeping the jaws pressed against said first-mentioned member and the gripping ends of the jaws pressed against each other.

One object of the invention is to provide a spring pin of this kind, wherein the requisite spring force between the jaws is produced with a minimum of spring material, while the stresses on said material are maintained within reasonable values. Another object of the invention is to provide a pin adapted for mass production, the individual parts of which are mutually held together perfectly in all directions.

The invention will be hereinafter more fully described with reference to the accompanying drawing, in which:

Figs. 1 and 2 are part sectional side views of a spring or clothes pin made in accordance with the invention and shown in two different positions of adjustment.

Fig. 3 shows a view of the inside of one jaw with the pin controlling members represented in section.

Fig. 4 is a perspective view of a somewhat modified clothes pin constructed according to the invention.

Referring to the figures reference numerals 10 and 12 designate the two jaws of the clothes pin, which are formed in known manner with opposed bevelled surfaces 14 at the ends of the gripping jaws of the pin. Immediately inwardly of said bevelled portions, the jaws are provided with rounded recesses 16 with which the clothes pin grips lines or the like. The opposite ends of the jaws—hereinafter termed the actuating ends—are tapered to an outwardly decreasing thickness. The jaws are provided, approximately centrally thereof, with inner shoulders 18 adjacent shallow recesses 20 disposed nearer the actuating ends. Preferably such recesses are rounded adjacent said shoulders and terminate, toward the actuating ends, in offsets 22.

Outside the recesses 20, the external sides of the jaws are formed with transversely extending grooves 24. Within such grooves is located a retaining ring or iron wire 26 bent around the jaws so as to hold the same slightly spaced apart. Disposed in the recesses 20 is a spring 28 of U-shape when viewed in the direction of the pivotal axes of the jaws, the bent portion of said spring being arranged adjacent the shoulders 18 and the free ends thereof pressing against the jaws.

2

In the embodiment shown in Figs. 1 to 3, the spring 28 is made of piano wire or the like which has been bent so as to form two opposed U's disposed in parallel planes, and interconnected at one jaw.

When the actuating ends of the jaws 10 and 12 are pressed toward each other from the position shown in Fig. 1 to that shown in Fig. 2, each pivots about an axis, said axes coinciding with portions of the iron wire 26 engaging the respective grooves 24. These pivotal axes are denoted by 30 and 32 in Fig. 2. The U-shaped spring 28 prevents the wire 26 from jumping out of the grooves 24 due to its pressure acting outwardly of the jaws. On the other hand, the wire 26 holds the spring against movement in a lateral direction. The pressure of the spring 28 acts upon the jaws of the clothes pin for some distance beyond the pivotal axes 30 and 32 towards the actuating ends, and will thus return the jaws to the position shown in Fig. 1.

Due to the fact that the turning movement of the jaws takes place about the axes 30 and 32 located on the outside thereof and that these axes are also on a level with the middle portion of the U-shaped spring 28, the important result is achieved that the recesses 20 and thus the spring are moved forwardly relative to said axes, that is to say towards the gripping end, as will be clearly seen from Figs. 1 and 2. Further, this results in the lever arm by which the free ends of the U-spring act upon the jaws about the pivot points 30 and 32 being reduced, so that the counter pressure of the spring, increased by the compression, is compensated for. In this manner it is possible to use a single spring, which consequently need not be wound in a number of convolutions.

When the actuating ends of the jaws are moved toward one another, the jaw portions located on the opposite side of the pivot axes 30 and 32 are moved apart. Since the middle portion of the U-spring is now situated on a level with the pivot axes or even projects slightly beyond the latter in a direction toward the actuating end, the portions of the walls of the recesses 20 located adjacent the shoulders 18 will also be moved apart. Thus, the middle portion of the spring 50 is not subjected to any compression during use of the clothes pin, its radius of curvature being, on the contrary, increased to some extent, which also favors the possibility of using a spring of small dimensions. The deformation of the 55 spring is distributed, as will be seen from Fig. 2,

inwardly over the normally straight portions of the U-spring.

The embodiment shown in Fig. 4 differs from that heretofore described solely by the feature that the U-spring 34 is in the form of a band or strip. The recesses 20 are preferably slightly hollowed-out, as indicated at 36, so that there will be no contact at these points, which facilitates the displacement of the U-spring in the lengthwise direction of the pin into its position on assembly, for instance in the case where the spring might have projecting burrs that might catch in the wooden material of the jaw.

What I claim is:

1. A clothes pin comprising a pair of opposed gripping jaws terminating in actuating extremities, the said jaws being provided on their inner faces and substantially centrally of the length thereof with opposed complementary recesses, each recess comprising a substantially straight side wall having a rounded shoulder directed toward the gripping jaws and an offset portion at the opposite extremity of the recess, a U-shaped spring seated within said recesses and engaging the opposed curved and side walls thereof for resiliently urging the jaws into gripping position, a transversely disposed retaining ring surrounding said jaws and U-shaped spring for securing the clothes pin in assembled relation, and means for preventing movement of said retaining ring lengthwise of said jaws, the retaining ring being so positioned that when the actuating extremities are compressed so as to open the gripping jaws the distance between the planes of the tips of the arms of the U-shaped spring and of the retaining ring is reduced.

2. A clothes pin comprising a pair of opposed gripping jaws terminating in actuating extremities, the said jaws being provided on their inner faces and substantially centrally of the length thereof with opposed complementary recesses, each recess comprising a substantially straight side wall having a rounded shoulder directed toward the gripping jaws and an offset portion at the opposite extremity of the recess, a U-shaped spring seated within said recesses and engaging the opposed curved and side walls thereof for resiliently urging the jaws into gripping position, retaining grooves on said jaws positioned sub-

stantially opposite the point where the straight wall of each recess merges with the rounded shoulder thereof, and a transversely disposed retaining ring having portions seated within said grooves and surrounding said jaws and U-shaped spring for securing the clothes pin in assembled relation, the retaining ring being so positioned that when the actuating extremities are compressed so as to open the gripping jaws the distance between the planes of the tips of the arms of the U-shaped spring and of the retaining ring is reduced.

3. A clothes pin comprising a pair of opposed gripping jaws terminating in actuating extremities, the said jaws being provided on their inner faces and substantially centrally of the length thereof with opposed complementary recesses, each recess forming offset portions at the extremities thereof, a U-shaped spring seated within said recesses and engaging the opposed walls thereof for urging the jaws into gripping position, the ends of said U-shaped spring extending toward said actuating extremities, retaining grooves on said jaw positioned opposite said spring, and a transversely disposed retaining ring having portions seated within said grooves and surrounding said jaws and U-shaped spring for securing the clothes pin in assembled relation and actuating said spring to resiliently urge the jaws into gripping position, the retaining ring being so positioned that when the actuating extremities are compressed so as to open the gripping jaws the distance between the planes of the ends of the U-shaped spring and of the retaining ring is reduced.
